CLAIM

The ornamental design for an electronic smoking article, as shown and described.

DESCRIPTION

FIG. 1 is a left end, perspective view of an electronic smoking article showing our new design.

FIG. 2 is a right end, perspective view thereof.

FIG. 3 is side elevational view thereof, the other side being a mirror image.

FIG. 4 is a left end elevational view thereof; and, FIG. 5 is a right end elevational view thereof.

The broken line showing illustrates portions of the electronic smoking article which form no part of the claimed design.
